CLAIM

The ornamental design for a lotion warmer, as shown and described.

DESCRIPTION

FIG. 1 is a side view of a lotion warmer showing my new design.

FIG. 2 is a front view of the lotion warmer.

FIG. 3 is a back view of the lotion warmer.

FIG. 4 is a top view of the lotion warmer; and, FIG. 5 is a bottom view of the lotion warmer.

The broken lines are shown for illustrative purposes only and form no part of the claimed design.
